UNITED STATES PATENT OFFICE.

GEORGE LESLIE FERRIS, OF McARTHUR, OHIO; O. E. VOLLENWEIDER ADMINISTRATOR
OF SAID FERRIS, DECEASED.

WASHING MACHINE.

Application filed May 8, 1922. Serial No. 559,293.

To all whom it may concern:

Be it known that I, GEORGE LESLIE FERRIS, a citizen of the United States, and a resident of McArthur, in the county of 5 Vinton and State of Ohio, have invented certain new and useful Improvements in Washing Machines, of which the following is a specification.

My invention relates to washing machines 10 of the type of construction in which a cylinder containing the articles to be cleaned is rotatably mounted within a casing containing a cleaning fluid, and it consists in the combinations, constructions and arrangements herein described and claimed.

An object of my invention is to provide 20 a washing machine having facilities permitting of the articles to be washed being conveniently placed within the cylinder or removed therefrom, without danger of injury to the person of the operator.

A further object of my invention is to provide a washing machine having simple and effective means operable at will to occasion the release of the driving mechanism 25 of the washing machine from the cylinder or the operative engagement of the driving mechanism with the cylinder.

A still further object of my invention is 30 to provide a washing machine having a casing adapted to be placed upon a heating device, such as a stove, to occasion the heating of a fluid within the casing to a desired degree, and which has means cooperating 35 with the casing for holding a cylinder disposed within the casing in a desired position while the articles to be washed are placed within or removed from the cylinder.

A still further object of my invention is 40 to provide in a washing machine of the character described, a novel cylinder and means for removably supporting the cylinder in a desired position within a fluid containing casing.

Other objects and advantages will be apparent from the following description and the novel features of the invention will be particularly outlined in the appended claim.

My invention is illustrated in the accompanying drawings, forming a part of this application, in which:

Fig. 1 is a perspective view of a practical embodiment of the invention,

Fig. 2 is an enlarged detail of a fragmentary portion of the end of the outer casing shown in Fig. 1, 55

Fig. 3 is a longitudinal vertical section through the embodiment of the invention shown in Fig. 1, showing a cylinder comprised therein in elevation, 60

Fig. 4 is a transverse vertical section through the embodiment of the invention shown in the preceding views, and

Figs. 5 to 8 inclusive, respectively are views similar to Figs. 1 to 4, inclusive, showing another embodiment of the same invention in which is comprised a novel means for connecting and disconnecting the driving mechanism of the device from the cylinder at will. 65

In carrying out my invention, I provide an outer casing 1 which has side and end walls and a bottom, being open at its upper end. The casing 1 is made of a light metal, or like material, and is shown in the drawings as being of rectangular form. The casing 1 is closed at its upper end when the device is in operation by a removable cover 2 having a depending marginal flange 3 adapted to have a friction-tight fit with a bead 4 formed along the upper edge of the casing. A handle 5 is superimposed upon the cover 2 intermediately of its length and adjacent to one side edge thereof, and this handle has a spring catch portion 6 depending below the plane of the cover adjacent to the edge thereof and being bent inwardly at its extremity, as at 7 (see Fig. 4) to engage the under side of the bead 4, whereby the cover 2 is releasably held against displacement from applied position upon the casing. 70

A pair of bracket bearings 8-8 are secured to the inner faces of the end walls of the casing and are provided with vertical slots or sockets open at their upper ends, such as indicated at 9, in which trunnions 10-10 carried at the opposite ends of a cylinder 11 in axial alignment with each other and with the cylinder may be disposed, the arrangement being such that the cylinder 11 is removably and rotatably supported within the casing 1. 95

The cylinder 11 consists of two complementary segmental sections 12 and 13, the section 13 being relatively small and being 100

attached to the section 12 along one edge by hinges 14, whereby the section 13 serves as a cover or closure for the cylinder and may be swung from the full line position shown in Fig. 4 to the dotted line position shown in the same figure. A hook 15 formed integrally with the section 13 or separately and secured thereto, is positioned on the outer periphery of the cylinder for engagement with one of the side walls of the casing at the upper edge of the latter when the cylinder is in the position in which illustrated in Fig. 4 and the cover section thereof has been swung into the dotted line position. The cylinder will thus be held against rotation while the cover section thereof is in raised position.

The cylinder 11 is formed with series of aligned openings 16 through its peripheral wall. A guard member 17 is provided for each series of openings 16. The guard members 17 are angular in cross section and are secured to the inner walls of the cylinder in position to prevent the articles to be washed from partially or entirely passing through the openings 16 while permitting the cleaning fluid employed to pass freely between the cylinder and the outer casing. Moreover, the guard members 17 tend to deflect the cleaning fluid within the cylinder toward the center thereof and thus aid in occasioning a thorough diffusion of the cleaning fluid through the articles to be washed.

It is desirable that the means for transmitting a driving force to the cylinder should be capable of disconnection from the latter conveniently and quickly and without the use of any tools. To this end, the cover 2 is cut away at 18 at one end thereof, to permit of a drive pinion 19 mounted upon a movably supported drive shaft 20 being partially disposed interiorly of the casing 1 in mesh with a large driven gear 21 which is carried at the end of the cylinder 11 in axial alignment with the latter. The drive shaft 20 is journaled in a sleeve bearing 22 adapted to rest upon the bead 4 at the upper edge of the end of the casing and being normally held against vertical movement relative to the casing by the engagement of a depending integral arm 23 thereof with the web portions of a U-shaped guide 24 which is formed integrally with and extends laterally of the face of a plate 25 secured to the end of the casing along the upper edge thereof, as clearly shown in Figs. 2 and 3. The arm 23 has a lateral lug or enlargement 26 underlying the lower edge of the guide bar 24 when the arm 23 is in the position in which illustrated in Fig. 2. The guide bar portion 24 is offset laterally at 27 adjacent to one end thereof to permit of the depending arm 23 being moved vertically and out of engagement

with the guide bar 24 when the bearing 22 has been slidably moved along the edge of the casing until the arm 23 is disposed between the offset end portion of the guide bar and the plate 25. A pivoted hook or catch 28 is adapted to engage with a projection 29 formed on the depending arm 23 to extend laterally thereof and to thus prevent the bearing 22 from being moved from the position in which illustrated in Fig. 2 toward the enlarged or offset portion of the guide 24.

A crank 30 is attached to the drive shaft 20 and may be conveniently grasped and operated to occasion a rotation of the cylinder 11.

From the foregoing description of the various parts of the device, the operation thereof may be readily understood. As stated, the casing 1 is made of sheet metal or the like and is adapted to be placed upon a stove or other source of heat. Handles 31-31 are secured to opposite ends of the casing to permit of the latter being conveniently moved. The cylinder 11 is provided with a rib 32 which is formed upon the cover section 13 at the end thereof remote from the end of the cylinder to which the gear 21 is secured. A spring catch or hasp 33 carried by the cover section 13 is adapted to engage with a stud 34 carried by the body portion 12 of the cylinder to releasably maintain the cover section in closed position. The cylinder may be conveniently grasped by means of the rib 32 and the gear 21 and deposited within the casing 1 with the trunnions 10-10 disposed within the slots or sockets of the bearings 9-9 and the cover section of the cylinder 13 uppermost. The cover section 13 may then be swung into open position, as illustrated by the dotted lines in Fig. 4, and engage with the side of the casing 1, which in the arrangement described and illustrated is the back side of the casing, thereby maintaining the cylinder 11 in the position in which illustrated in Fig. 4 while the articles to be washed are placed therewithin. The casing 1 may now be or may have been previously partially filled with a liquid, such as water, to which soap or the like may be added. The bearing 22 is placed upon the end of the casing with the arm 23 pending between the enlarged or offset portion of the guide 24 and the face of the plate 25 and is then moved slidably along the bead at the upper edge of the end of the casing until the gear or drive pinion 19 is in mesh with the gear 21. The latch or hook 28 is then placed in engagement with the projection 29 and the gear 19 will be held in mesh with the gear 21. It will be understood of course that the handle 30 is attached to the shaft 20 carried by the bearing 22 and is moved bodily with the latter. The cover section 13 may now be disengaged

from the casing 1 and fastened in closed position. The cover or lid 2 will now be placed upon the casing and the crank 30 is operated after the contents of the casing 1 has been heated to a desired degree, whereby the cylinder 11 will be rotated and the contents thereof cleaned. It will be understood that steam will form within the interior of the casing 1 during the operation of the device. When the cleaning operation has been completed, the handle 5 is grasped and the downwardly and forwardly directed force or pressure is applied thereto, thereby tilting the cover 2 at the back edge thereof to permit of the escape of steam from the interior of the casing before the cover 2 has been fully raised and without the hands or person of the operator being exposed to the action of the heated steam. When the cover 2 has been removed, the cover section 13 of the cylinder may be swung into open position and engage with the casing 1 in the manner described. The articles within the cylinder may then be removed without danger of injury, as by scalding, to the hands or person of the operator. When it is desired to remove the cylinder from the casing 1, the latch or hook 28 is disengaged from the projection 29, the bearing 22 is slidably moved along the bead 4 until the arm 23 may be moved vertically through the relatively wide or offset portion of the guide 24 and the crank 30, the bearing 22, shaft 20, and the gear 19 are moved as a unit. The cylinder 11 may then be lifted from the casing 1. It will be observed that the removal of the cylinder from the casing or the disengaging of the driving mechanism from the cylinder requires the use of no tool and may be conveniently and quickly accomplished.

Referring now to Figs. 5 to 8, inclusive, I show another embodiment of the same invention in which is comprised a means for releasably connecting the drive mechanism of the device with the cylinder which means is different in details from that embodied in the form of the device heretobefore described.

The same reference numerals have been used to designate identical parts of the two forms of the device illustrated in the drawings and I shall confine my description of the form of the device exhibited in Figs. 5 to 8 inclusive to the parts thereof that differ from analogous parts of the first form of the device.

One of the bracket bearings 8—8 is provided with upstanding extensions 35 supporting a horizontal plate 36 which is superimposed upon the bead 4 at the end of the casing and which may be formed integrally with the extension 35. The plate 36 is provided at its outer edge with a pair of horizontally spaced lugs 37—37 and a rod 38 is mounted at its ends in the lugs.

The sleeve bearing 22 in which the drive shaft 20 is journalled is provided with a tangential plate portion 39 adapted to lie flatwise upon the plate 36. Horizontally spaced depending lug extensions 40—40 are integral with the plate 39 at one edge of the plate 39 and are rotatably mounted upon the rod 38 whereby the plate 39 is swingingly supported upon the plate 36 and can be moved from a position in which disposed flat upon the latter, as illustrated in Figs. 5, 7 and 8, into outwardly swung positions, as illustrated in Fig. 6. When the plate 39 is in the position in which illustrated in Figs. 5, 7 and 8, the drive pinion 19 which is carried by the drive shaft 20 will be held in mesh with the driven gear 21 of the cylinder 11 and the cylinder is held against displacement from the position in which rotatably disposed in the casing. When the plate 39 is in outwardly swung position, the pinion 19 is positioned out of engagement with the gear 21 and out of position to obstruct the cylinder when it is desired to remove the latter from the casing.

A friction catch or latch 41 is pivoted intermediately at 42 upon the plate 36 and comprises an end portion 43 and a handle portion 44. The handle portion 44 is adapted to be grasped and manipulated to conveniently swing the end portion 43 into and out of position to clampingly hold the plate 39 in superimposed relation to the plate 36. When the end portion 43 is in operative engagement with the plate 39, the latter will be securely held against the plate 36. An upstanding lug 45 may be provided upon the end portion 43 to receive a pressure tending to facilitate the manipulation of the latch to move the end portion 43 therefrom into and out of latching position.

It will be understood that the casing or container 1 may be suitably reenforced or stiffened in any suitable known manner to preclude the possibility of the spreading of the opposite sides or ends thereof or the distortion of the walls thereof in service or while being transported from place to place, without departing from the spirit and scope of the invention.

Obviously, my invention is susceptible of embodiment in forms other than that illustrated in the accompanying drawings, and I therefore consider as my own, all modifications and adaptations of the form of the device disclosed herein which fairly fall within the scope of the appended claim.

I claim:

In a washing machine, a casing adapted to receive a cleaning fluid, a cylinder rotatably and removably supported within the casing, a driven gear carried by said cylinder at one end thereof in concentric relation therewith, a plate supported upon the

end of the casing proximate to the driven gear, a bearing having a portion adapted to rest upon the plate, a drive shaft journaled in said bearing, a drive gear carried by said drive shaft in position to mesh with said driven gear when the said portion of the bearing is resting upon said plate and to be disengaged therefrom when the

inner end of the bearing is swung upwardly and outwardly in respect to said plate, means for swingingly attaching the bearing at its outer end to the plate, and a pivoted latch for releasably holding the bearing superimposed upon the plate. 10

GEORGE LESLIE FERRIS.
